Primary Examiner — Karen E Kearney*Assistant Examiner* — John M Otte(57) **CLAIM**

The ornamental design for a production inkjet printer screen with user interface, as shown and described.

DESCRIPTION

FIG. 1 is a front view of a production inkjet printer screen with user interface in accordance with the present invention; FIG. 2 is a front view of a second embodiment thereof; FIG. 3 is a front view of a third embodiment thereof; and, FIG. 4 is a front view of a fourth embodiment thereof. The broken lines in the drawings represent unclaimed environmental subject matter and form no part of the claimed design.
